UNITED STATES PATENT OFFICE.

HENRY W. GARNSEY AND JOHN M. TRACY, OF ROCHESTER, NEW YORK.

AUTOMATIC SAFETY CURTAIN APPLIANCE.

SPECIFICATION forming part of Letters Patent No. 778,852, dated January 3, 1905.

Application filed April 28, 1904. Serial No. 205,307.

To all whom it may concern:

Be it known that we, HENRY W. GARNSEY and JOHN M. TRACY, citizens of the United States, residing at Rochester, in the county of Monroe and the State of New York, have invented a new and useful Automatic Safety Curtain Appliance, of which the following is a specification.

This invention relates to safety attachments designed to be used in connection with a fire-proof stage-curtain. The attachment comprises a hinged cover adapted to cover the slot in which the lower edge of the curtain rests when the curtain is raised, the cover descending within the slot when the curtain is lowered, and the attachment also comprises a plurality of guides adapted to lie horizontally when the curtain is raised and to stand vertically adjacent the outer edge of the slot as the curtain is lowered and to guide the curtain into the slot, preventing draft from the stage outward bulging the curtain toward the foot-lights and throwing the lower edge of the curtain out of alignment with the slot.

The object of the invention is to cover the slot flush with the stage when the stage is being used and to guide the curtain into the slot when same is being lowered.

The invention consists in the novel features of construction and combination of parts hereinafter shown and described, particularly pointed out in the claims, and shown in the accompanying drawings, in which—

Figure 1 is a vertical elevation of a curtain, showing diagrammatically the mechanism for raising and lowering the curtain, the lower edge of the curtain resting in the slot, as shown by dotted lines, and showing the relative position occupied by our attachment for raising and lowering the slot-cover. Fig. 2 is a detail perspective view of a portion of a stage, showing the slot and the guides for guiding the lower edge of the curtain to the slot. Fig. 3 is a detail view of our slot-cover and means for actuating same, the parts being shown in vertical elevation, a portion of the fire-wall and stage-floor being shown in section. Fig. 4 is a detail vertical section of the stage-floor, taken through and at right angles to the footlights and slot. Fig. 5 is a detail

section taken horizontally through the fire-wall and curtain-guide at one side of the proscenium-arch.

In the drawings, A represents the proscenium-arch, the lower portion on one side of the stage only being shown, and A' the fire-proof curtain. The arch is provided with the vertical guide-flange A², which guides the vertical sides of the curtain in its ascent and descent. Extending across the stage beneath the lower edge of the curtain is a slot or well B, in which the lower edge of the curtain A' rests when the curtain is fully lowered.

A movable cover C fits within the slot B, the cover C having a plurality of hinges C' hinged to its under side, and these hinges are also hinged to the bottom of the slot B, as shown most clearly in Fig. 3. The slot B is of greater length than the cover C, and when the cover is moved in one direction the hinges C' fold down upon the bottom of the slot B and the cover C rests in the lower portion of the slot B upon the folded hinges, as shown in dotted lines in Fig. 3. Reverse movement draws the cover upward, bringing the hinges C' into the vertical position, (shown by the full lines in Fig. 3,) and they then serve as supports for the cover C, which lies in the slot B flush with the floor of the stage and forming a continuation of same, bridging the slot B. To effect this movement of the cover automatically, we pivot to the inner side of the proscenium-arch A a bell-crank lever D, the pivotal point being at the juncture of the long and short arms of the bell-crank, and to the free end of the short arm is pivoted an end of a link D', the opposite end of the link being pivotally secured to the adjacent end of the cover C. A triangular-shaped bracket E is slidably arranged upon a vertical bar E', the main curtain-cable F passing loosely through the bracket. The cable F carries a weight F', which descends as the curtain rises and engages the bracket E, sliding same downward on the bar E'. The curtain-cable F and weight F' are parts of the curtain-actuating mechanism. A cable G is attached at one end to the bracket E and after passing over the idle pulley G' has its opposite end secured to the free end of the long arm of the

bell-crank D. A weight G² is secured to the cable G of sufficient weight to draw the bracket E upward when the weight F' is raised and to aid in forcing downward the long arm of the bell-crank, the lowermost position of the weight G² and the long arm of the bell-crank D being shown in dotted lines in Fig. 3.

Parallel to and adjacent the outer edge of the slot B extends a rotatable rod H, held in place by staples H' and having rigidly secured thereto guide-fingers H², the upper portions of the fingers H² being curved, so that when turned down into a horizontal position the outer ends of the guide-fingers H² lie in the footlight-trough J, as is clearly shown in Fig. 4. When elevated, the upper portion of these fingers curve away from the curtain, as shown in Fig. 2. A lever H³ is secured to the rod H, and through the movement of the said lever the rod is rotated through a quarter-revolution, raising or lowering the guide-fingers, the object of these fingers being to prevent the lower edge of the curtain A' from bulging outward from any cause, and thus preventing its seating itself in the slot B.

Having thus fully described our invention, what we claim, and desire to secure by Letters Patent, is—

1. The combination with a curtain and stage, the stage being slotted, a hinged cover working in the slot, a bell-crank pivotally hung adjacent said cover, a link connecting an end of the cover to an arm of the bell-crank, and means for automatically actuating the bell-crank.

2. The combination with a stage and curtain therefor, the said stage having a slot adapted to receive the lower edge of the curtain, a cover adapted to move vertically in the said slot, and means for automatically raising the said cover as the curtain rises.

3. The combination with a stage having a curtain and curtain-lowering mechanism, the stage having a slot adapted to receive the

lower edge of the curtain, of a cover adapted to move vertically in the slot and to lie flush with the upper surface of the stage when the curtain is raised, and means connected to the cover, and adapted to be actuated by the curtain-lowering mechanism, adapted to lower the cover into the slot on descent of the curtain.

4. The combination with a stage having a curtain-receiving slot and curtain-actuating mechanism, of a cover adapted to work in the said slot, hinges hinged to the bottom of the slot and to the under side of the cover, a bell-crank, a link pivotally connected to the cover and the bell-crank, a vertically-slidable bracket adapted to be actuated by the curtain mechanism, a cable connecting the bracket and the bell-crank, and a weight on the cable adapted to return the bracket to its normal position on rise of the curtain.

5. In combination with a stage having a curtain and curtain-receiving slot, of a rod arranged parallel to the outer edge of the said slot, fingers secured to the said rod the outer portions of the fingers being curved, and means for partially rotating the said rod, as and for the purpose set forth.

6. The combination with a stage having a curtain and a slot to receive the lower edge of the curtain, of a cover adapted to work in the slot, and means working in the slot adapted to automatically raise and lower the cover simultaneously with movement of the curtain, a rotatable rod arranged adjacent and parallel to the slot, curved fingers carried by the rod, and means for rotating the rod and elevating the fingers when the cover is lowered, as and for the purpose set forth.

H. W. GARNSEY.
J. M. TRACY.
